(57) **CLAIM**

The ornamental design for a knife holder, as shown and described.

DESCRIPTION

FIG. 1 is a perspective view, from the front, of my new design;

FIG. 2 is a perspective view, from the rear, thereof;

FIG. 3 is a top plan view thereof;

FIG. 4 is a left side elevational view thereof;

FIG. 5 is a bottom plan view thereof;

FIG. 6 is a rear elevational view thereof;

FIG. 7 is a front elevational view thereof; and,

FIG. 8 is a perspective view of an alternate embodiment of my new design.

The broken lines showing the knives are for illustrative purposes only and form no part of the claimed design.
